CLAIM

The ornamental design for a solar panel cable retention clip, as shown and described.

DESCRIPTION

FIG. 1 is a lower perspective view of an example solar panel cable retention clip with broken lines showing a portion of a solar panel assembly to illustrate an example environment; FIG. 2 is an upper perspective view of the solar panel cable retention clip of FIG. 1;

FIG. 3 is a front view of the solar panel cable retention clip of FIG. 1;

FIG. 4 is a rear view of the solar panel cable retention clip of FIG. 1;

FIG. 5 is a left-side view of the solar panel cable retention clip of FIG. 1;

FIG. 6 is a right-side view of the solar panel cable retention clip of FIG. 1;

FIG. 7 is a top view of the solar panel cable retention clip of FIG. 1; and,

FIG. 8 is a bottom view of the solar panel cable retention clip of FIG. 1.

The broken lines shown in the figures are for illustrative purposes only and form no part of the claimed design.
